FRANK D. CHAPMAN, OF BERLIN, WISCONSIN.

CONTINUOUS COOKER.

Application filed March 15, 1926. Serial No. 84,898.

This invention relates to improvements in continuous cookers.

It is one of the objects of the present invention to provide a continuous cooker having air and steam operated inlet and discharge valves for charging cans into the cooker and discharging cans therefrom.

A further object of the invention is to provide a continuous cooker in which jets of air, water or steam are used to force the cans into the cooker and to discharge the cans therefrom.

A further object of the invention is to provide a continuous cooker in which the air and steam pipes are positioned within the axial portions of the can inlet and discharging valves.

A further object of the invention is to provide a continuous cooker which is of simple construction, is strong and durable and is well adapted for the purpose described.

With the above and other objects in view, the invention consists of the improved continuous cooker and its parts and combinations as set forth in the claims, and all equivalents thereof.

In the accompanying drawings in which the same reference characters indicate the same parts in all of the views:

Fig. 1 is a top view of the improved continuous cooker;

Fig. 2 is an end view thereof, parts broken away and other parts being shown in section to illustrate interior construction;

Fig. 3 is an end view of the cooker;

Fig. 4 is a top view partly in section, of the discharge end portion of the cooker; and

Fig. 5 is a similar view of the charging end portion thereof.

Referring to the drawing, the numeral 8 indicates a horizontally extending cylindrical cooker receptacle or drum which is mounted on supports 9 and is provided with an inlet opening 10 at its upper portion adjacent one end, and an outlet opening 11 at the lower end portion of the drum, adjacent its other end. Said openings are above the water level maintained in said drum. The tank is provided with a rotary carrier 12 formed of spoked spiders 13 (only one being shown) mounted on a shaft 14, and longitudinally extending angle bars 15 which are connected to the spaced spiders and each bar has one of its angled portions extending radially, and the other circumferentially.

Said bars extend in parallel relation to the shaft of the carrier and are of less distance apart than the diameter of the cans or food containers 16, so that said cans cannot pass therebetween. The bars coact with a spirally trending guide track member 17 which is positioned within the drum and surrounds the carrier and is connected to the inner periphery of the drum. The said guiding member is formed of metal of T-shape in cross section with the stem portion 17' of the T extending radially inwardly to form a continuous end guide for the cans, while the outer cross section portions 17" form guides for the side edge portions of the cans. The convolutions of the spiral member are spaced apart a sufficient distance to permit a can to roll on the cross portions and between the stems while being moved by the carrier and advanced by the spiral member. The charging opening 10 is provided with a rotary valve 18 enclosed in a cylindrical valve casing 19 mounted on the drum. The valve is also of cylindrical form in cross section and closely fits the casing and is formed with radial opening can pockets 20 for receiving cans to be processed. The upper portion of the valve casing is formed with an inlet opening 21 for receiving the cans. An inclined trough 22 extends from a point of supply upwardly to the valve casing and over the drum to form a support for the cans 16 which are fed to the valve by an endless chain 23. Said chain extends in a vertical plane around the drum and is formed with transverse bars 24 which directly engage the cans. The valve 18 is formed with a bore 25 for receiving a steam pipe 26 having a jet opening 27 in alignment with a radial duct 28 leading to and in communication with the bottom portions of the can pockets 20 to blow the cans out of said pockets in successive order when the pockets turn into register with the opening 10 of the drum, as clearly shown in Fig. 2. The pocket valve and the steam pipe 26 form a valve 26', and as each valve pocket turns into register with the drum opening 10, its duct 28 will move into register with the jet opening 27 and permit the escape of steam therethrough to force the cans out of the pockets and into the rotary carrier 12.

The cans in traveling around the inner side of the drum will be moved endwise by the spiral member 17 from the inlet opening 10 to the outlet opening 11 of the drum.

2
A can discharge valve 29 of cylindrical form in cross section is positioned adjacent the discharge opening and is formed with radial opening can pockets 30 for receiving cans 5 from the discharge opening of the drum without permitting the escape of the heating steam within the drum.

A cylindrical valve casing 31 encloses the valve and the drum discharge opening 11 10 and is formed with a downwardly extending discharge opening 32 through which the cans are discharged. The discharge valve 29 is formed with a bore 32' for receiving a steam pipe 33 having a jet opening 34 in 15 alignment and communication, successively, with radial ducts 35 formed in the valve member and extending from the bore 32 to the bottom portions of the can pockets 30, so that as said jet opening and ducts come 20 into register, a jet of air from the pipe 33 will force the cans in successive order out of the pockets.

An air or steam jet is also used for forcing the cans from the carrier into the discharge valve 29 and to accomplish this result, a tube 34 extends into the end portion of the drum and terminates within the carrier and has a jet opening 35 in radial alignment with the discharge opening 11 of the 25 drum. The discharge of air or steam through said tube coincident with the can pockets registering with the discharge opening of the drum, is controlled by a valve 36 and actuated in timed relation to the pockets 30 by a cam member 38. The cam 38 is mounted on and driven by the shaft 39 which rotates the discharge valve 29. A shaft 40 rotates the inlet can valve 19 and both shafts have a 35 geared connection 42 with a driving shaft 41 and journaled on the drum. Said driving shaft 40 also has a geared driving connection 43 with the carrier 12 within the drum, and the geared connection 42, and is provided with pulleys 44 for belted connection with a 45 source of power. A shaft 45 geared to and extending from the geared connection 42 to the opposite end of the drum, is provided with a chain wheel 46 for driving the feed chain 23.

50 Steam is supplied to the drum through pipe 47, and water by pipe 48. A gauge 49 indicates the level of water within the drum.

In use the drum is partly filled with hot water and steam is supplied to the drum to 55 maintain the temperature desired. The cans of food are now fed into the inlet valve by the endless chain and will drop by gravity into the pockets of the valve, and the said valve in rotating will carry them into the 60 drum. When each can in successive order is in register with the drum inlet opening, the can will drop by gravity into the carrier, and to make a more positive feed, jets of steam, air or water are directed against the cans to 65 force them out of the pockets in successive

order and into the carrier. The steam pressure within the drum may be greater than atmospheric pressure if desired, and by varying the level of hot water within the drum, the cans in passing through the water in 70 their passage through the drum will be subjected to more or less heat and will roll on the inner portion of the drum a greater or less extent to give the desired amount of agitation, thus permitting control of the heating and agitation. Upon arriving at the discharge opening of the drum, the jets of steam, water or air in addition to gravity will cause the cans to drop from the carrier into the pockets of the discharge valve and 75 said valve in rotating will carry the cans to the discharge opening of the discharge valve. Upon arriving at this point, the cans will drop out of the pockets by gravity and will also be forced out of the pockets by the jets 80 of compressed air or other fluid under pressure.

85 From the foregoing description, it will be seen that the cans are forced into the drum and carrier by steam or other fluid pressure and are discharged from the carrier and the drum and the discharge valve by steam, water or air under pressure. In feeding the cans into or discharging the cans from the drum, the valves prevent the loss of any material amount of the heating medium within the drum. The material within the cans is cooked while the cans are passing through the drum, and the degree of cooking can be controlled by the speed of travel of the cans 90 through the drum and the amount of hot water within the drum so that the cooking operation is a continuous one and that the cans may be fed to and discharged from the drum continuously.

100 What I claim as my invention is:

1. A cooker, comprising a drum for receiving a heating medium and having an inlet opening and a discharge opening, a carrier within the drum, an inlet valve adjacent the inlet opening, a fluid pressure means for moving the cans from the valve to the carrier, an outlet valve adjacent the discharge opening of the drum, and a fluid pressure means for moving cans from the carrier to the discharge valve and from the discharge valve outwardly.

110 2. A cooker, comprising a drum for receiving a heating medium and having an inlet opening and a discharge opening, a carrier within the drum for moving cans from the inlet opening to the outlet opening, an inlet valve adjacent the inlet opening of the drum and having pockets for receiving cans, a fluid pressure means for moving the same from the pockets to the carrier, an outlet valve adjacent the discharge opening of the drum and having pockets for receiving cans, and a fluid pressure means for moving cans 115 from the inlet valve pockets to the carrier 120

and from the carrier to the outlet valve pockets and also from the said pockets outwardly therefrom.

3. A cooker, comprising a drum for receiving a heating medium and having an inlet opening and a discharge opening, a rotary carrier within the drum for moving cans from the inlet to the discharge opening, an inlet valve adjacent the inlet opening of the drum and having pockets for receiving cans and ducts in communication with said pockets, means for supplying a fluid under pressure to said ducts to force the cans from the pockets to the carrier, an outlet valve adjacent the discharge opening of the drum and having pockets for receiving cans and ducts in communication with said pockets, and means for supplying a fluid under pressure to said ducts to force the cans out of said pockets.

4. A cooker, comprising a horizontal drum for receiving a heating medium and having an inlet opening and a discharge opening, a rotary carrier within the drum for moving cans from the inlet to the discharge opening, an inlet valve adjacent the inlet opening of the drum and having pockets for receiving cans and ducts in communication with said pockets, means for supplying a fluid pressure to said ducts to force the cans from the pockets to the carrier, an outlet valve adjacent the discharge opening of the drum and having pockets for receiving cans and ducts in communication with the pockets, a fluid pressure means for forcing the cans from the carrier into the pockets of the discharge valve, and means for supplying a fluid under pressure to the ducts of the discharge valve to force the cans out of the pockets of said valve.

5. A cooker, comprising a horizontal drum for receiving a heating medium and having an inlet opening and a discharge opening, a rotary carrier within the drum for moving cans from the inlet to the discharge opening, a rotary inlet valve adjacent the inlet opening of the drum and having pockets for receiving cans and a bore and ducts in communication with said pockets, a fluid pressure pipe extending into the bore and having an opening positioned to successively register with the ducts of the valve, an outlet valve adjacent the discharge opening of the drum and having pockets for receiving cans and a bore and ducts in communication with said pockets, a fluid pressure pipe extending into the bore and having an opening positioned to successively register with the ducts of the discharge valve, means for feeding cans to the inlet valve, and means for rotating the carrier and the valves.

6. A cooker, comprising a horizontal drum for receiving a heating medium and having an inlet opening and a discharge opening, a rotary carrier within the drum for moving

cans from the inlet to the discharge opening, a rotary inlet valve adjacent the inlet opening of the drum and having pockets for receiving cans and a bore and ducts in communication with said pockets, a fluid pressure pipe extending into the bore and having an opening positioned to successively register with the ducts of the valve, a fluid pressure pipe extending to a position within the discharge end portion of the carrier and having an opening for directing the pressure fluid against the cans at the point of discharge of said cans and in successive order, a valve controlling the flow of fluid from said last mentioned pipe, an outlet valve adjacent the discharge opening of the drum and having pockets for receiving cans and a bore and ducts in communication with said pockets, a fluid pressure pipe extending into the bore and having an opening positioned to successively register with the ducts of the discharge valve, means for feeding cans to the inlet valve, and means for rotating the carrier and the valves.

7. A cooker, comprising a horizontal drum for receiving a heating medium and having an inlet opening and a discharge opening, a rotary carrier within the drum for moving cans from the inlet to the discharge opening, a rotary inlet valve adjacent the inlet opening of the drum and having pockets for receiving cans and a bore and ducts in communication with said pockets, a fluid pressure pipe extending into the bore and having an opening positioned to successively register with the ducts of the valve, a fluid pressure pipe extending to a position within the discharge end portion of the carrier and having an opening for directing the pressure fluid against the cans at the point of discharge of said cans and in successive order, a valve controlling the flow of fluid from said last mentioned pipe, an outlet valve adjacent the discharge opening of the drum and having pockets for receiving cans and a bore and ducts in communication with said pockets, a fluid pressure pipe extending into the bore and having an opening positioned to successively register with the ducts of the discharge valve, means for feeding cans to the inlet valve, and means for rotating the carrier and the valves.

8. A cooker, comprising a horizontal drum for receiving a heating medium and having an inlet in its upper portion near one end and a discharge opening in its lower portion near its opposite end, a rotary carrier within the drum and co-acting therewith to move cans fed thereto from the inlet opening to the discharge opening, a rotary inlet valve adjacent the inlet opening and having radial pockets for receiving cans and ducts in communication with said pockets, said valve also having a bore and ducts

- extending from the bore to the pockets, a fluid pressure pipe extending into the bore and having an opening positioned to successively register with the ducts of the valve, 5 a fluid pressure pipe extending to a position adjacent the discharge end of the carrier and having an opening for directing the pressure fluid against the cans at the point of discharge of said cans and in successive order, a valve automatically controlling the flow of fluid from said last mentioned pipe, a rotatable outlet valve positioned adjacent the outlet opening and having radial pockets for receiving cans and 15 ducts in communication with said pockets, said outlet valve also having a bore and ducts extending from the bore to the pockets, a fluid pressure pipe extending into the outlet valve bore and having an opening 20 positioned to successively register with the ducts of the discharge valve, means for feeding cans to the inlet valve in successive order, and means for rotating the carrier and the valves.
- 25 9. A cooker, comprising a drum for receiving a heating medium and having an inlet opening and an inlet valve adjacent said opening, said drum also having an outlet opening, a carrier for moving cans from the inlet opening to the outlet opening, an outlet valve adjacent the outlet opening, and a fluid pressure means for moving cans from the inlet valve to the carrier, from the carrier to the outlet valve and also out of 30 the outlet valve.
10. A cooker, comprising a drum for receiving a heating medium and having an inlet opening and an inlet valve adjacent said opening, said drum also having an outlet opening, a carrier for moving cans from the inlet opening to the outlet opening, an outlet valve adjacent the outlet opening, a fluid pressure means for moving cans from the inlet valve to the carrier, means for moving cans from the carrier to the discharge valve, and fluid pressure means for moving cans from the discharge valve.
- 40 11. A cooker, comprising a drum for receiving a heating medium and having an inlet opening and an inlet valve adjacent said opening, said drum also having an outlet opening, a carrier for moving cans from the inlet opening to the outlet opening, an outlet valve adjacent the outlet opening and having peripheral pockets for receiving and moving cans from the inlet opening through the heating medium and to the outlet opening, an outlet valve adjacent the outlet opening and having can pockets, and a fluid pressure means for forcibly moving cans from the pockets of the inlet valve to the carrier pockets.
- 45 12. A cooker, comprising a drum for receiving a heating medium and having an inlet opening and an inlet valve adjacent said opening, said drum also having an outlet opening, a carrier having peripheral pockets for receiving and moving cans from the inlet opening through the heating medium and to the outlet opening, an outlet valve adjacent the outlet opening and having can pockets, and a fluid pressure means for forcibly moving cans from the pockets of the inlet valve to the carrier pockets.
- 50 13. A cooker, comprising a drum for receiving a heating medium and having an inlet opening and an inlet valve adjacent said opening, said drum also having an outlet opening, a carrier having peripheral pockets for receiving and moving cans from the inlet opening through the heating medium and to the outlet opening, an outlet valve adjacent the outlet opening and having peripheral pockets, and a fluid pressure means for forcibly moving cans from the pockets of the outlet valve outwardly.
- 55 14. A cooker, comprising a drum for receiving a heating medium and having an inlet opening and an inlet valve adjacent said opening, said drum also having an outlet opening, a carrier having peripheral pockets for receiving and moving cans from the inlet opening through the heating medium and to the outlet opening, an outlet valve adjacent the outlet opening and having peripheral pockets, and a fluid pressure means for forcibly moving cans from the pockets of the carrier to the pockets of the outlet valve.
- 60 In testimony whereof, I affix my signature.
- 65 FRANK D. CHAPMAN.
